SOLENOID CONSTRUCTION

Raymond S. Miller and Kamill Seidel, Detroit,
Mich., assignors to Vickers Incorporated, De-
troit, Mich., a corporation of Michigan

Application July 21, 1941, Serial No. 403,352

7 Claims. (Cl. 175—341)

This invention relates to solenoid construction and more particularly to a method of forming a solenoid housing and to the housing so formed.

Commercial solenoid construction in the past few years has been subject to considerable criticism due to the fact that the solenoids would not stand up under the increasingly severe commercial requirements. Many efforts have been made to correct this situation by changing the solenoid construction but none of these has been completely successful. It is an object of the present invention to provide a solenoid which has a suitable housing construction from the point of view of strength and which has a novel magnetic circuit for the magnetic flux of the solenoid.

Another object of the invention is the construction of a solenoid in which the physical dimensions, weight and operating temperature are at a minimum for a definite amount of pounds pull or torque.

In solenoid construction it is extremely desirable to use a magnetic circuit made up of thin laminae in order to reduce the eddy currents and keep the iron loss at a minimum. On the other hand, it is desirable to keep the magnetic circuit as short as possible and also to provide a housing along with the circuit which protects the electric coil both from the point of view of conducting the heat away from the coil and keeping air and dirt out of the operating mechanism. The so-called window frame type of solenoid construction is well known, that is, the type in which a frame of laminae is used to surround the coil. Another type has recently come into use and that is the solenoid circular iron housing, this latter type has the advantages of providing a complete covering for the construction but has caused considerable loss from heat due to eddy currents and other magnetic losses. The present invention contemplates a solenoid housing which combines the advantages of the laminated structure with the solenoid housing structure and which achieves the ideal result of a minimum eddy current loss, low iron loss, a short magnetic path, low operating temperature, and light weight.

There are numerous other advantages which flow from the construction to be herein described but no attempt is made here to enumerate all the advantages.

Other objects and features of the invention will be disclosed as the description of the device progresses.

In the drawings:

Fig. 1 is a sectional assembly view of the completed device.

Figs. 2 and 3 are sectional views taken on lines 2—2 and 3—3, respectively, of Fig. 1.

Figs. 4 and 5 are end and side elevations respectively of the magnetic material which goes into the solenoid.

Fig. 6 illustrates the condition of the housing and magnetic material prior to the machining operation.

Fig. 7 is a sectional view of the construction of Fig. 6.

Fig. 8 is an end view of the housing after machining, showing the recess which receives the solenoid in assembly.

Fig. 9 is a partial perspective of the end plate showing the detailed construction thereof.

In Fig. 4, four blocks, A, B, C and D are shown arranged in spaced relation around an imaginary axis E. These blocks are held in their respective positions by angles 10 and braces 11. These blocks A, B, C and D are formed of a magnetic material and may be of solid iron. They are preferably formed of L-shaped pieces of laminations of iron as shown in the drawings. The next step in the manufacture of the housings is the forming of a casing around the magnetic blocks. This casing is shown at 15, Fig. 6. This casing may be applied around the blocks in a die-casting operation or a molding process. Fundamentally, the step consists of placing the blocks within some kind of a mold and either forcing or pouring the casing material into such mold while in a molten or plastic state and then allowing it to set or harden. A core is used to eliminate the necessity for boring out the entire center. The material forming the housing 15 is to be a non-magnetic material. If metal is used, aluminum has been found to be suitable. Another suitable substance is the class of materials which is commonly called plastics, one of which is Bakelite.

Other suitable means may be used to space and arrange the blocks prior to the molding process.

After the casting or molding operation, the block is machined to have an internal bore 16, as shown in Fig. 8. The bore does not pass completely through the block but terminates in a wall 17 which has an aperture 18. The magnetic circuit of the housing is completed by two additional blocks of laminated material F and G, shown in Fig. 2, arranged in transverse relation and jointed together in such a way that the ends thereof will register with the end blocks A, B, C and D. A cap 20 is provided with a recess for receiving the members F and G and for positioning the same.

A magnetic pole piece 21 is held against the center portion of the blocks by a bolt 22. The cap

28 is preferably formed of the same material as the housing 15, that is, a non-magnetic material. Bolts 23 hold the cap on to the housing.

The cap 20 with the pieces F and G completes the magnetic circuits at one end of the assembly while the other ends of the circuits are completed by the portions of blocks A, B, C and D which make up wall 17 (Fig. 8). While the arrangement described is preferred, it will be seen that separate end pieces could be used at both ends of the circuits.

A solenoid winding 24 is received in the bore 16 of the housing 15. A non-magnetic sleeve 25, for example of brass, is inserted within the solenoid winding. This sleeve is sealed at one end by a compressible gasket 26 and at the other end by a compressible gasket 27. These gaskets are made slightly compressible to permit the parts to be drawn tightly together in connection with a member 28a which forms part of the complete assembly and may, for example, be a body of a valve. Within the sleeve 25 is the slotted solenoid core 28 which reciprocates back and forth when the solenoid is energized and may be connected to or integral with the movable member of a valve. Suitable lead wires are taken from the solenoid core through an opening 29 in the cap 20, see Fig. 2. The ends of the members F and G are positioned in openings 30 machined in the cap 20 (see Fig. 9). It will thus be seen that there is formed a solenoid assembly in which the solenoid core 28 and the inside of the sleeve 25 are sealed from the solenoid. This prevents any oil or foreign matter which may be in the sleeve from leaking in the winding. If desired the members F and G may also be cast into the cap 20.

A soft washer 35 is placed between members 15 and 20 to seal the inside of the solenoid from dirt and dust. This washer is preferably of the soft material which will permit the bolts 23 to tighten the members F and G tightly against the ends of the members A, B, C and D of housing 15. It also permits the sealing of the compressible seals 26 and 27.

It will be seen that the above described construction provides many paths for the magnetic flux and, in addition, it can flow in more than one plane. The path, however, of the flux is a short path with a minimum of air gaps. In fact, the only air gaps that exist are those between the members A, B, C and D and the transverse G and F. Since this air gap can be reduced to a minimum by the forcing of the parts together in assembly, it does not involve a serious loss. Since these air gaps are reduced to a minimum by the forcing of the parts together in assembly, the magnetizing current is reduced to a minimum thereby diminishing the no-load losses considerably. Therefore, the windings of the coil can be maintained at a minimum and more of the effective current put into the solenoid is transferred into actual pull. In addition, it will be seen that the solenoid is completely protected from outside dirt and air and that the use of a light material for the housing, such as aluminum or plastic will reduce the overall weight considerably. In addition, the laminations are rigidly secured against vibration and loosening.

We claim:

1. A solenoid construction comprising a casing of non-magnetic material, fields of laminated magnetic material embedded in said casing in spaced relation around a central bore therein, a solenoid winding in said bore, means at the end

of said winding in said bore for forming an end pole comprising longitudinal blocks of laminated magnetic material arranged in transverse relation and positioned whereby the ends thereof register with the magnetic material in said main housing, a magnetic pole piece on said blocks, and a cap for maintaining said blocks in position relative to said main housing.

2. A solenoid construction comprising a casing 10 of non-magnetic material such as aluminum, fields of laminated magnetic material embedded in said casing in spaced relation around a central bore therein, a solenoid winding in said bore, means at the end of said winding in said 15 bore for forming an end pole comprising longitudinal blocks of laminated magnetic material arranged in transverse relation and positioned whereby the ends thereof register with the magnetic material in said main housing, a magnetic 20 pole piece on said blocks, and a cap for maintaining said blocks in position relative to said main housing, and means holding said cap in place comprising bolts extending from said cap into said embedding material independently of 25 said field laminations.

3. A solenoid construction comprising a casing 30 of non-magnetic material such as aluminum, fields of magnetic material embedded in said casing in spaced relation around a central bore 35 therein, said material comprising L-shaped laminations arranged in groups, a solenoid winding in said bore for forming an end pole comprising longitudinal blocks of magnetic material arranged in transverse relation and positioned whereby the ends thereof register with the magnetic material in said main housing, a magnetic pole piece on said blocks, and means formed of non-magnetic material for maintaining said 40 blocks in position relative to said housing.

4. The method of forming a solenoid housing 45 which comprises arranging corner to corner L-ends of elongated blocks of magnetic material parallel to, and in spaced relation around, an imaginary locus, surrounding said pieces in a non-magnetic material in a plastic state, hardening said material to embed said blocks firmly, and machining blocks and the embedding material to provide an opening to receive a solenoid 50 winding.

5. The method of forming a housing for an 55 electrical device dependent on electrical fields for operation which comprises arranging pieces of magnetic material in spaced relation around an imaginary locus, fastening said pieces together with suitable means to hold them in spaced relation, surrounding said pieces in a non-magnetic material in a molten or plastic state, hardening said material to embed said blocks firmly, and machining the magnetic material and the embedding material to provide an opening to receive an electrical element.

6. A housing for a cylindrical solenoid winding 65 comprising a plurality of sets of L-shaped iron laminæ arranged in opposed pairs around an axis, a non-magnetic material embedding said laminæ, one leg of each lamina extending parallel to the axis adjacent the outside of the winding and the other leg extending radially toward the axis at one end of the winding, a plurality 70 of interlocked sets of laminæ arranged diametrically of the axis, each set having its ends positioned adjacent the ends of opposed pairs of parallel legs of the L-shaped lamina, and means on 75 said interlocked laminæ and within said wind-

ing to form a pole piece for a solenoid plunger operating within said winding.

7. A housing for a cylindrical solenoid winding comprising a plurality of sets of L-shaped iron laminae arranged in opposed pairs around an axis, angle means extending between adjacently spaced sets to maintain the same in position, means embedding said angle means and said sets of laminae leaving the inward faces of

the laminae exposed, a plurality of interlocked sets of laminae arranged radially of the axis, each set having its ends positioned adjacent the ends of the opposed pairs of L-shaped laminae, and means on said interlocked laminae and within said winding to form a pole piece for a solenoid plunger operating within said winding.
